UNITED STATES PATENT OFFICE.

JAMES GRANT CHALMERS, OF VANCOUVER, BRITISH COLUMBIA, CANADA.

CIGARETTE-MAKING MACHINE.

1,316,830.

Specification of Letters Patent. Patented Sept. 23, 1919.

Application filed September 25, 1918. Serial No. 255,694.

To all whom it may concern:

Be it known that I, JAMES GRANT CHALMERS, a subject of the King of Great Britain, and a resident of the city of Vancouver, in the Province of British Columbia, Canada, have invented certain new and useful Improvements in Cigarette-Making Machines, of which the following is a specification.

My invention relates to improvements in cigarette making machines, and the object of my invention is to provide a simply constructed and operated device capable of being conveniently carried about the person by means of which completed cigarettes may be quickly and perfectly manufactured by the smoker, which device is adapted to contain both a supply of tobacco and a packet of cigarette papers and is besides provided with means for moistening the gummed edge 20 of the papers.

I attain this object by the construction illustrated in the accompanying drawings in which—

Figure 1 is a view of the machine, closed. Fig. 2 is a longitudinal sectional view of the machine.

Fig. 3 is a sectional plan view.

Fig. 4 is a perspective view showing the apron and packet of papers in place, the 30 cover plate being removed.

Fig. 5 is a perspective view showing a paper in place ready to receive the tobacco.

Fig. 6 is a plan view of the device ready for inversion.

Similar figures of reference indicate similar parts throughout the several views.

1 indicates the casing of the machine, formed preferably as shown and having an opening 2 in its upper side adapted to be 40 partially closed by a plate 3 mounted for longitudinal movement on the casing, the outer end of which plate is turned downwardly as at 5 in Fig. 2 and reduced in width to form with the sides of the casing 45 slots 6 and 7, as shown in Fig. 6. Disposed within the casing adjacent its front end is a tube 8 of less width than the casing so that it is capable of lateral movement therein, which tube contains mucilage and is fitted 50 with a withdrawable plunger 9 adapted to extend through one side of the casing and a projection 10 extending through a slot 11 in the bottom of the casing, by means of which projection the tube may be moved laterally 55 to project the end of the plunger beyond the side of the casing so that it may be

gripped and withdrawn, as more fully described hereinafter. The tube 8 forms a rest for the upper edge of a packet of cigarette papers 12 disposed on an inclination within the casing and transversely of the same, the lower bound edge of the packet resting on the bottom of the casing and held against rearward movement by blocks 13 and 14 secured to the sides, as shown in Figs. 2, 3 65 and 4.

15 indicates a round bar disposed above the tube 8 and extending from side to side of the casing, around which bar passes an apron 16 formed of any suitable material 70 having secured to each end gripping handles 17 and 18, the handle 17 being formed as a flat plate having clips 19 and 20 on its underside and adapted to coöperate with the plate 3 to completely close the opening 2, as 75 shown in Figs. 1 and 2, while the handle 18 is formed as an open frame having a transverse bar 21 by means of which a space 22 is provided in the frame, this member not only forming a grip for the pulling of 80 the apron when rolling the cigarette but also acting as a paperweight to hold the cigarette paper 23 in its proper position when inverting the casing to deposit the tobacco thereon. The rear portion of the casing forms a 85 chamber to hold the tobacco, as indicated by the numeral 24 in Figs. 2, 3, and 4.

The manner in which my device operates may be described briefly as follows. When closed the machine is as shown in Fig. 1, 90 the opening 2 being then closed by the plates 3 and 17 and the plate 17 being detachably locked to the plate 3 owing to the engagement of its clips 19 and 20 with the forward edge of plate 3, this engagement being 95 effected when closing the machine. Suppose now, the chamber 24 containing tobacco and the packet of cigarettes being in place, as shown, with the apron folded down on to the top side of the packet, it is desired to 100 make a cigarette. The plate 17 is disengaged from plate 3 and plate 3 is slid back allowing the apron to be unfolded and laid over the end of the casing so that the packet 12 may be opened and a paper taken therefrom. The inner end of the apron to which 105 is secured the frame 18 is then laid on top of the packet 12 and the outer end pulled outwardly until the portion remaining within the casing is just sufficient to cover 110 the packet, when the cigarette paper 23 is then laid on the apron and the frame swung

down thereonto to hold it in place, the upper edge of the paper 23 then lying within the space 22. The tube 8 is then moved laterally so as to enable the plunger 5 to be withdrawn, the moist end of which is then drawn along the edge of the paper to moisten and gum the same, the transverse bar 21 and upper bar of the frame acting as guides for the stroke of the plunger, 10 after which it may be returned into the tube and the tube retracted to its normal position. The cover plate 3 is then slid forward and the machine inverted, thus depositing tobacco from the chamber 24 on to the paper 15 23, the operation being finally completed by then swinging the frame 18 first upwardly in the slots 6 and 7 and then pulling it outwardly while pressing downwardly on the cover plate to prevent spilling and to tighten 20 the apron, this action having the effect of rolling the paper tightly around the tobacco so that a perfectly formed and gummed cigarette is discharged from the machine, the turned down end 5 of the plate 3 springing slightly upwardly to permit of the exit 25 of the cigarette from the machine.

What I claim as my invention is:

1. In a cigarette making machine, a casing 30 adapted to contain a packet of cigarette papers and divided thereby into two compartments the rear one of which forms a container for tobacco, a longitudinally movable apron connected within the front com-

partment one end of which is adapted to be laid on top of said packet to receive a 35 flat paper on which tobacco is deposited by the inversion of the machine and to be drawn outwardly to roll said paper around the tobacco, and a gripping handle for drawing said end outwardly, said handle 40 adapted to lie on said paper during such inversion.

2. In a cigarette making machine, a casing having an opening in its upper face provided with a slideable cover plate partially 45 closing said opening, said casing being adapted to contain a packet of cigarette papers and divided thereby into two compartments the rear one of which forms a container for tobacco, a longitudinally mov- 50 able apron connected within the front compartment one end of which is adapted to be laid on top of said packet to receive a flat paper on which tobacco is deposited by the inversion of the machine and to be 55 drawn outwardly to roll said paper around the tobacco, a gripping handle on said end for drawing the same outwardly, said handle being adapted to lie on said paper during inversion, and a plate on the opposite 60 end of the apron adapted for detachable engagement with the said cover plate to complete the closure of the casing opening.

Dated at Vancouver, B. C., this 5th day of September, 1918.

JAMES GRANT CHALMERS.
